US00D848615S

(12) **United States Design Patent** (10) Patent No.: **US D848,615 S**
(45) Date of Patent: **** May 14, 2019**

(54) **IV POLE ATTACHMENT DEVICE**

(71) Applicant: **Clinical Biotechnology Research Institute at RSFH**, Charleston, SC (US)

(72) Inventors: **Lauren McNeill**, Mt. Pleasant, SC (US); **Christopher Lienhop**, Wilmington, NC (US); **Andrea H. Marshall**, Mt. Pleasant, SC (US); **Krista Herndon**, Summerville, SC (US)

(73) Assignee: **Clinical Biotechnology Research Institute at RSFH**, Charleston, SC (US)

(**) Term: **15 Years**

(21) Appl. No.: **29/637,413**

(22) Filed: **Feb. 18, 2018**

Related U.S. Application Data

(63) Continuation-in-part of application No. 15/240,006, filed on Aug. 18, 2016, now Pat. No. 9,895,485.

(57) **CLAIM**

The design for an IV pole attachment device, as shown and described.

DESCRIPTION

FIG. 1 is an isometric view of the claimed IV pole attachment device, embodying the present design;

FIG. 2 is a top down plan view thereof;

FIG. 3 is a bottom up plan view thereof;

FIG. 4 is a right side view thereof;

FIG. 5 is a left side view thereof;

FIG. 6 is a front side view thereof view thereof; and,

FIG. 7 is a rear side view thereof view thereof.

1 Claim, 6 Drawing Sheets
